DESCRIPTION

FIG. 1 is a front elevational view of the computer translator for audio tape of the present invention;

FIG. 2 is a back elevational view of the computer translator for audio tape of FIG. 1;

FIG. 3 is a left side elevational view of the computer translator for audio tape of FIG. 1;

FIG. 4 is a right side elevational view of the computer translator for audio tape of FIG. 1;

FIG. 5 is a top plan view of the computer translator for audio tape of FIG. 1; and,

FIG. 6 is a bottom plan view of the computer translator for audio tape of FIG. 1.
